CAPSULE MAKING MACHINE

Edward A. Ravenscroft, Glencoe, and Ferdinand H. Young, Lake Bluff, Ill., assignors to Abbott Laboratories, Chicago, Ill., a corporation of Illinois

Application March 12, 1937, Serial No. 130,534

11 Claims. (Cl. 18—5)

Our invention relates generally to machines for manufacturing filled capsules and is particularly concerned with, although not necessarily limited to, machines for manufacturing capsules of predetermined and controllable shapes or forms which are provided with walls of gelatine or similar material and which are filled with liquid medicaments or the like. In its broadest aspects the present invention is an improvement upon the capsule making machine disclosed in our co-pending application, Serial No. 123,098, which was filed on January 30, 1937, and which is assigned to the assignee of the present invention.

As we pointed out in the above identified application, vast numbers of capsules filled with medicaments are used in the pharmaceutical and drug industries, and for many years there has been a great need for a capsule making machine which when supplied with suitable raw materials would automatically manufacture filled capsules of uniform size at relatively high speeds and at low cost, while at the same time assuring the preservation of absolutely sanitary conditions throughout the manufacturing operation. This need has been substantially met by the capsule making machine disclosed in our co-pending application, Serial No. 123,098.

However, the machine disclosed in that application possesses certain inherent limitations. Particularly, the machine, as designed, manufactures capsules which are pillow shaped and is substantially incapable of manufacturing capsules of any other shape. Since this shape is somewhat different from the shape of the capsules in common use at the present time, there is considerable doubt as to whether or not the consuming public could be prevailed upon to adopt and use such capsules, and the machine while fully operative is of doubtful commercial value. Accordingly, the principal object of the present invention is to provide an improved, fully automatic capsule making machine which shall possess all of the advantages of the capsule making machine disclosed in our co-pending application, but which at the same time shall be inherently capable of forming the capsules made by it to any desired shape or configuration.

By virtue of the ability of the machine of the present invention to manufacture capsules having definite and controllable shapes or forms, it is possible to mark capsules manufactured by the machine with suitable identifying marks or the like as an incident to their manufacture. The provision of means for accomplishing such

marking constitutes another of the objects of the present invention, and it might be mentioned at this point that heretofore it has been considered impractical, if not impossible, to provide capsules of the subject type with external identifying marks. 5

Other objects of our invention are to provide a simple, foolproof machine capable of accomplishing the above stated objects and capable of continuous operation over long periods of time 10 with little or no supervision by the operator; to provide an improved capsule making machine which may be easily cleaned and sterilized and which can be changed over from the manufacture of capsules filled with one medicament or 15 other filling material to the manufacture of capsules filled with a different filling material within a relatively short period of time and with little or no adjustment; to provide a capsule making machine of the subject type which shall effectively utilize the raw materials with which it is supplied with little or no waste and without the formation of the so-called "nets" formed during the operation of the machines at present known to the art; and, generally, to provide an improved machine for manufacturing filled capsules, especially capsules of predetermined shapes. 20

One structural embodiment of our invention is illustrated in the accompanying drawings. Referring to these drawings, 30

Figure 1 is a diagrammatic view illustrating a capsule making machine in accordance with the present invention, together with certain auxiliary apparatus;

Figure 2 is an enlarged, fragmentary sectional view showing certain of the structural features of the capsule making machine illustrated generally in Figure 1; 35

Figure 13 is a fragmentary perspective view illustrating the features of a modified form of mold;

Figures 14 and 15 are perspective views of two types of capsules, one spherical and the other ellipsoidal, which may be readily manufactured by the apparatus of the present invention; and

Figure 16 is a perspective view illustrating one manner in which capsules manufactured by the machine of our invention may be marked with an identifying letter or design as an incident to their manufacture.

Reduced to its simplest elements, the capsule making machine of the present invention operates by forming a relatively thin walled, hollow tube of gelatine or other suitable capsule envelope material, at least a portion of which tube is formed within a hollow mold adapted to produce a finished capsule of the desired shape or form, filling this tube, preferably as it is formed, with a filling material supplied under sufficient pressure to cause the portion of the tube which is located within the mold to expand and fill that mold, and then cutting off the portion of the tube located within the mold so as to form a capsule. The apparatus includes means for opening the mold, for removing the finished capsule from the mold, and for automatically restoring the several structural elements of the machine to an operative condition following the manufacture of each individual capsule. This mode of operation results in a device having a plurality of intermittently moving, mechanical elements, and certain of the mechanical arrangements utilized for accomplishing this intermittent movement constitute important features of the invention.

The shape of the hollow tube formed by the machine is preferably, but not necessarily, cylindrical. In the machine illustrated in the drawings the tube is formed by extrusion, and at the point of formation has a diameter materially less than the cross sectional dimensions of the mold cavity, i. e., the cross sectional dimensions of the finished capsule. This arrangement aids in producing a thin walled tube and also in assuring proper shaping of the capsule by the mold. As will be pointed out in some detail later, the formation of a filled tube which is cut off at regular intervals to provide for the capsules manufactured thereby assures the effective utilization of substantially all of the raw materials with which the machine is supplied and overcomes the waste

and need for reclaiming the materials making up the nets formed during the operation of the prior art devices.

Referring to the drawings, the capsule forming machine illustrated therein includes a hopper or reservoir 1 which is closed at its top and which is adapted to hold a quantity of the gelatine or other material, indicated at 2 in Figure 2, utilized in forming the tube which serves as the enclosing envelope or casing for the capsules. The hopper or reservoir 1 is jacketed, as is illustrated particularly at 3 in Figure 2, and terminates in a flange 5 which is bolted to the upper end of a jacketed gear pump 7. The lower end of the gear pump 7 connects with an extrusion orifice mechanism 9 the walls of which are also jacketed.

The details of the jacketed orifice mechanism 9 are illustrated particularly in Figures 2 and 3, and it will be seen that this mechanism includes a hollow, generally annularly shaped body member 10, preferably of cast metal, which is provided with a centrally arranged passageway 11, conically flared at its upper end, for receiving a tube forming element 13 and for defining the outer walls of the tube forming orifice proper. The orifice mechanism is fixedly held in place at the lower end of the pump 7 by means of four bolts 14 which are adapted to extend entirely through the body member 10. The pump 7 and the reservoir or hopper 1 in turn are rigidly supported upon a suitable bed plate 15 which serves as the main frame for the entire structure. The annular inner passageway 16 formed within the body member 10 serves as a jacket for the tube forming portions of the mechanism.

The tube forming element 13 includes a hollow, generally conically shaped body member adapted to fit within the upper conical portion of the passageway 11 and a pipe or tube 17 supported centrally within the body member by means of three symmetrically arranged arms 18 (Figure 3) between which the gelatine or other wall forming material is conducted to the outlet of the orifice mechanism. The tube forming element 13 is removable as a unit from the passageway 11 so as to permit the substitution therefor of other similarly proportioned elements adapted to produce tubes of differing size and, if desired, may be provided with keying means to assure its proper positioning within the passageway 11. The upper end of the pipe 17 is adapted to connect with a horizontal passageway 19 formed in the top wall of the member 10.

The medicament or other liquid or semi-liquid filling material is supplied to the capsule making machine proper from a suitable closed reservoir 21 by means of a variable stroke, intermittently operated, piston pump 23, illustrated in Figures 1, 6, and 12, suitable piping 25 serving to connect the filling material reservoir 21 and the pump 23 with the passageway 19 in the body 10 of the orifice mechanism 9.

The cutters utilized in conjunction with the machine illustrated in the drawings comprise a pair of oppositely arranged, elongated knives 27 which are adapted to be slidably supported directly beneath the outlet of the orifice mechanism 9 by means, such as the tongue and groove connection 29 illustrated particularly in Figures 4 and 10.

To lubricate the tongue and groove connection 29 and to prevent sticking of the knives 27 to the walls of the gelatine tube or to the capsule during the cutting operation, means is provided whereby lubricating oil may be applied directly

to the knives 27 during their operation. As illustrated in the drawings, this means includes a pair of L-shaped passageways 31 formed in the body 10 of the orifice mechanism and adapted 5 to be connected to a suitable source of lubricating oil as by the piping 32 illustrated particularly in Figure 1. Any neutral mineral oil of the proper viscosity may be utilized for accomplishing this lubrication.

10 As mentioned previously, one of the important objects of our invention is to provide means for controlling and determining the form or shape of the capsules manufactured by the machine. This means constitutes, in the apparatus illustrated in the drawings, a pair of mold members 15 15 33 (Figures 6, 7, and 11) which may be of metal adapted to be pivotally supported upon the main frame 15 in opposed cooperative relationship. The support means constitutes four pivot pins 20 or stub shafts 35 which are supported upon and keyed to suitable brackets 37 formed integrally with the frame 15 of the machine. These mold members 33 are movable from the normal position shown in Figure 7 to the position shown in Figure 9, which latter figure illustrates the extreme separation of those members and is the position to which they are moved following the formation and the cutting off of each of the capsules. Suitably proportioned cavities 38 within 25 the free end of each of the mold members determine the shape of the capsules formed by the machine. The mold members 33 are removable so as to permit the substitution therefor of similarly proportioned members having mold cavities 30 of other shapes.

Each of the mold members 35 is provided with an ejector mechanism for aiding in effecting disengagement of the capsule from the mold following its formation. The ejector mechanisms 40 comprise elongated plunger members 39 slidably supported within suitable recesses 41 formed in the body of the mold and biased to a normal inoperative position by a suitable spring 42. The outer end of each of the plunger members 39 45 is adapted to ride against a suitably proportioned cam 43 fixedly supported upon the supporting shafts 35 for the mold member 33 with which it is associated, as is illustrated in Figures 7 and 9. Each of the plunger members 39 is thus automatically moved by the cam 43 against which it bears to effect removal of the capsule as an 50 incident to the opening of the mold members.

To prevent sticking of the capsules to the mold members 33 and to generally improve the operation of the machine, spray nozzles 45 are arranged for spraying suitable mineral oil into the mold cavities when the mold members 33 are in the separated position (Figure 9).

In the machine described in our co-pending application Serial No. 123,098, the capsule forming operation is carried on substantially continuously, this method of operation being made possible primarily because rotary cutters are used and because the capsules are not formed to any particular shape. In the machine of the present invention, however, the capsule formation is carried out by steps primarily because of the capsule molding function inherent therein. In general the operation of the machine of the present invention is substantially as follows: With the various structural elements in the position shown in Figure 2, the gear pump 7 for forcing the gelatine or other envelope forming material through the tube forming orifice mechanism 9 70 and the piston pump 23 for the medicament or

other filling material are operated simultaneously to form a relatively thin walled tube of gelatine at the lower end of the orifice mechanism 9. This tube is filled with the medicament or other filling material introduced into the interior of the 5 tube under sufficient pressure to cause the portion of the tube extruded into the mold cavity to swell sufficiently to completely fill that cavity. When this has been accomplished, further feed of the gelatine and the medicament is stopped 10 and the cutter knives 27 are moved from the normal position shown in Figure 2 to the position shown in Figure 8 to accomplish the cutting off of the end portion of the filled tube which is located within the mold cavity to form the 15 capsule and to accomplish the sealing off of the filled tube at the lower end of the orifice mechanism. Then, while the cutter knives 27 are retained in the engaged position in order to close the end of the tube forming orifice, the mold 20 members 33 are moved from the position shown in Figures 7 and 8 to the position shown in Figure 9 thereby accomplishing the discharge of the formed capsule from the mold cavity. The capsule preferably falls into a trough 47 leading 25 into a suitable receptacle or container or the like pending the packaging of the capsules. The mold members 33 are then returned to their normal position, and the cutter knives 27 moved back away from the open end of the orifice. Upon the 30 completion of these operations the cycle may be repeated.

The means for accomplishing the actuation of the several elements of the mechanism in the sequence described above includes a pair of drive 35 shafts 49 journaled in suitable bearings 50 at either end of the frame 15. The shafts 49 are arranged in generally parallel relationship and are both actuated simultaneously through the agency of a connecting shaft 51 and suitable bevel 40 gears 53. The connecting shaft 51 is also journaled upon the main frame 15 of the apparatus as by the bearings 54 (Figure 6), and is adapted to be directly driven by a variable speed electric motor 55 through the agency of a chain and 45 sprocket drive 57.

The medicament or filling material pump 23 is provided with check valves so arranged that the filling material can be discharged only into the orifice mechanism. Intermittent operation 50 of this pump is accomplished by a cam member 59 which is keyed to the upper end of the right hand (Figure 6) drive shaft 49. This cam 59 is engaged by a suitable roller follower 60 or the like affixed to the end of a pivoted lever 61, the 55 outer end of which is provided with a fork 63 for engaging the piston rod of the medicament pump 23. The lever 61 is pivotally supported intermediate its length upon an adjustable bracket 65, and by reference to Figures 5 and 6, it will 60 be seen that variation in the stroke of the pump 23 may be readily accomplished by adjusting the fulcrum of the lever 61 with reference to the cam 59.

Intermittent movement of the gear pump 7 65 for the gelatine or other material 2 utilized in forming the walls of the capsule is effected simultaneously with the intermittent movement of the medicament pump 23 through the agency of a train of gears indicated generally at 66, 70 the first two elements of which train, the driving gear 67 and the first driven gear 69, are mated. The driving gear 67 is keyed to the rear end of the left hand drive shaft 49, as is illustrated particularly in Figures 2, 6, and 7. The 75

relative position of the gears 67 and 69 at the beginning of the gelatine extruding or tube forming operation is illustrated in Figure 2, and it will be seen that the teeth of the unmutilated portion 70 of the driving gear 67 are just about to engage one of the two unmutilated segments 71 of the second gear 69. Thus, during the interval when the driving gear 67 rotates clockwise from the position shown in Figure 2 to the position shown in Figure 7, the gelatine pump 7 will be operated, the pump thus acting as a measuring pump during the tube forming operation. While this movement of the gelatine pump 7 is taking place, the drive cam 59 for the filling material pump 23 is also being operated to fill the extruded tube. As soon as the gears 67 and 69 have moved from the position shown in Figure 2 to the position shown in Figure 7, the mutilated sections 73 and 74 of the driving gear 67 and the second gear 69 engage, and further operation of the gelatine pump 7 is stopped until the mutilated section 73 of the driving gear 67 has been turned completely past the co-operating mutilated section 74 on the second gear 69.

As mentioned previously, the cutter knives 27 are slidably supported by a tongue and groove connection 29 immediately beneath the orifice mechanism 9. Each of the knives is rigidly attached at its outer end to a fork member 75 adapted to straddle the adjacent drive shaft 49. These fork members 75 are provided with suitable cam followers 76 for engaging the slots 77 in cams 79 which are keyed to each of the drive shafts 49, and the cams 79 are so arranged that during the movement of the drive shafts 49 from the position shown in Figure 7, which figure illustrates the position of the mechanism at the conclusion of the extrusion and filling operation, to the position shown in Figure 8 the knives 27 are moved toward each other so as to accomplish the cutting off of the end of the filled tube formed within the mold cavity and the simultaneous sealing off of the upper end of the capsule formed by the cutting operation. This operation also effects the sealing of the lower end of the gelatine tube at the orifice mechanism.

The cam slots 77 are so shaped that the knives 27 after being moved toward each other to sever the capsule from the tube are held in engagement with each other during the opening and closing of the mold.

The opening of the mold is accomplished through the use of a second pair of forked members 81 which are provided at their inner ends with racks 83 adapted to engage with teeth 85 formed in the hub of each of the mold members 33. The racks 83 are held in engagement with the teeth 85 by suitable guide members 87 bolted to the bracket supports 37 for the mold supporting shafts 35 as is illustrated particularly in Figures 6, 9, and 10. Movement of the forked members 81 and the racks 83 integral therewith is effected by a pair of cam members 81 having suitably shaped slots 89 adapted to be engaged by followers 91 affixed to the forked end of the members 81. These slots 89 are so proportioned that immediately following the cutting operation the molds 33 are rotated about their supporting pivots away from each other, and at the extreme position of this movement take the position shown in Figure 9. The actuation of the ejector plungers 39 is accomplished simultaneously with the opening movement of the mold members 33 by virtue of the engagement between the outer

ends of the ejector plungers and the operating cams 43 therefor.

At least when the mold members 33 are in the open position (Figure 9) they are sprayed with mineral oil. Further movement of the drive shafts 49 from the position shown in Figure 9 serves to successively restore the mold members 33 to their normal position beneath the orifice mechanism 9 and to withdraw the knives 27 from engagement with each other, this last movement being accomplished substantially at the point where the teeth of the unmutilated section 70 of the main drive gear 67 for the gelatine pump 7 are about to engage with the teeth of the adjacent unmutilated section 71 of the second gear 69 in the train 66. As soon as this engagement takes place the entire cycle of operation described in the foregoing is repeated.

To accomplish the most satisfactory operation of the machine of our invention, it is desirable to maintain accurate temperature control of the gelatine or other material used for forming the walls of the filled capsule and of the filling material and the orifice mechanism 9 during the operation of the machine. The gelatine in the reservoir 1 and in the gelatine pump 7 are preferably maintained at the same temperature, this temperature being, of course, sufficiently high to keep the gelatine in a liquid or semi-liquid state. The orifice mechanism 9 is preferably maintained at a somewhat lower temperature. This aids in accomplishing slight setting of the gelatine or other envelope material as it is forced through the orifice mechanism 9 by the pump 7. The temperature of the filling material may be maintained the same as the temperature of the orifice mechanism 9 or even somewhat lower.

These temperature differentials may be best accomplished through the use of an exchanger system for circulating a suitable liquid through the jackets of the gelatine reservoir 1 and the gelatine pump, a second heat exchanger system for circulating a liquid through the jacket of the orifice mechanism 9, and a third heat exchanger system for circulating a liquid through the jacket of the supply reservoir 21 for the filling material. These three heat exchanger devices are illustrated diagrammatically in Figure 1. Each of the systems includes a reservoir 95, a motor driven circulating pump 97, piping such as indicated at 99 for connecting each of the heat exchanger systems with the jackets of the respective parts, and an adjustable thermal switch control 101 for controlling the temperature of the liquid circulated through the jackets. Water may be conveniently used in the systems, and the heating may be supplied by electrical immersion heaters controlled by the thermal switches 101. It is desirable, but not essential, that the piping and jackets shall be covered with thermal insulation.

Suitable indicating thermometers 103 are provided for aiding in attaining accurate control of the temperature of the gelatine, the filling material, and the orifice mechanism. It has been found that the control of the several temperatures may be best accomplished by placing the thermometers in the fluid circuits of the heat exchangers, and such an arrangement is illustrated in the drawings.

It is desirable that the entire equipment shall be operated in a room or enclosure wherein the temperature and the humidity may be accurately controlled. Such an enclosure is illustrated at 105 in Figure 1, suitable air conditioning appa-

ratus for accomplishing humidity and temperature control being indicated at 107.

It is a property of gelatine when it is maintained at the proper temperature that the cutting off of a tube, such as is formed by the present machine, will at the same time seal both of the cut surfaces. This property is, of course, of great importance in accomplishing the satisfactory operation of the machine of our invention, 10 for the reason that it assures the sealing off of the end of the extruded tube and the sealing of the capsule as an incident to the severing of each capsule from the tube. It is also a property of gelatine that it may be stretched comparatively 15 easily. Thus, the cross sectional dimension of the tube formed at the orifice mechanism 9 may be maintained considerably smaller than the cross sectional dimension of the capsule which it is desired to form by the machine. The formation 20 of a small diameter tube in this manner aids in accomplishing the best possible shaping of the capsule, and also assures that the walls of the capsule shall be relatively thin.

In the apparatus of our invention, it is a relatively simple matter to accomplish the marking of the capsules formed thereby with a design, insignia, letter, or the like. Under certain circumstances this may be accomplished merely by the provision of a suitable raised or cut out portion 30 in the mold cavities 38. However, the best results are usually obtained through the utilization of an electrically heated mold insert 109 such as is illustrated particularly in Figure 13. By raising the temperature of the mold a slight 35 amount adjacent the portion therein in which it is desired to form the mark, a freer flow of the gelatine at such portion, and hence a better marking of the capsule, will be attained. A marked capsule produced by a heated insert such 40 as is illustrated in Figure 13 is illustrated in Figure 16. The oil spray for the mold members 33 effectively prevents sticking of the capsule to the heated section of the insert.

The maintenance of proper temperature 45 throughout the operation of the machine is, as mentioned previously, of very great importance in assuring satisfactory operation of the apparatus. Experiments indicate that particularly good results can be accomplished if the gelatine 50 in the hopper or reservoir 1 and in the measuring pump 7 is maintained at a temperature within the range of about 125° F. to 130° F. and if the gelatine at the orifice is maintained at a temperature within the range of 100° F. to 110° F. The 55 exact temperature to be used, of course, depends upon the composition of the gelatine or other envelope forming material. The medicament or other filling material and the lubricating oil for the sprays and the knives are preferably fed at the same temperature as that maintained in the orifice mechanism 9.

It will be noted that the discharge passageway 60 for the gelatine pump is of relatively small diameter and that the distance between the pump gears and the orifice mechanism is relatively 65 short. This is an important feature, for the reason that it minimizes the volume of gelatine which is maintained under pressure during the operation of the pump. Gelatine, in addition to its other properties, may be very materially compressed and unless the volume of gelatine under 70 pressure is kept within relatively small limits, some difficulty may be experienced in maintaining even capsule formation by the machine.

The pump 23 for the filling material serves to

75 maintain the filling material within the gelatine tube under pressure during the cutting off operation. This assures proper shaping and filling of the capsules. When the machine is started up it is, of course, necessary to accomplish the sealing off of the ends of the tube as it is formed. Usually this will result automatically from the first cutting operation, and ordinarily not more than one defective capsule will be formed.

The fact that the filling material is introduced 10 into the tube under considerable pressure makes possible the formation of capsules of almost any conceivable shape. The importance of this from the viewpoint of identification and from the standpoint of a merchandizing feature is, of 15 course, apparent. Also, the fact that the medicament or other filling material is introduced into the capsule under considerable pressure assures a smooth appearance to the outer wall of the capsule which is also desirable from a merchandizing viewpoint.

While we have disclosed a gear pump for forcing the gelatine or other wall forming material through the tube forming orifice, it will be apparent to those skilled in the art that various 25 other arrangements may be satisfactorily accomplished for this purpose. For example, the gelatine or other material may be moved through the orifice mechanism 9 by an intermittently operated plunger pump or by some arrangement 30 utilizing valves and a weighted plunger or air pressure.

The machine of our invention may be easily cleaned and sterilized. The flow paths of the gelatine and of the filling material are very short 35 and easily reached. If it is desired to stop the operation of the machine so as to change over to the use of another filling material, it is necessary merely to stop the flow of filling material, to operate the machine for a short interval 40 of time so as to clean out the remaining filling material which may be contained therein, wash out the filling material conduits and the pump 23 by a suitable washing agent, and then proceed with the manufacture of the capsules filled with a 45 different material. Experience shows that the machine may be changed over from one filling material to another within a very few minutes.

About any of the known types of liquid or semi-liquid filling materials which are capable of being 50 pumped can be used in the machine of the present invention with very satisfactory results. Accordingly when the term "liquid filled capsule" is used herein it will be understood to include 55 capsules filled with any liquid, semi-liquid, plastic, or paste filling material.

The machine of the present invention is relatively compact, and since the raw materials are completely enclosed within the mechanism of the machine during the entire capsule forming operation, it is possible to carry out the manufacture 60 of capsules under very highly aseptic conditions. Further, the mechanical arrangements utilized are simple and capable of easy access for repair, adjustment, or cleaning.

The apparatus of the present invention particularly lends itself to quantity production methods since a number of gelatine pump and orifice mechanism units may be arranged side by side and operated from a single gelatine reservoir and by a single driving mechanism. The heat exchanging units in such multiple installation may, of course, be readily arranged to accommodate additional capsule forming equipment.

It will be apparent to those skilled in the art that various machines may be evolved embodying the principles disclosed in the foregoing, and it is our intention, therefore, that the accompanying claims shall be accorded the broadest reasonable construction consistent with the state of the art.

We claim the following as our invention:

1. The method of manufacturing liquid filled, soft gelatine capsules which consists in extruding a relatively thin-walled tube of gelatine directly into a mold cavity of the same shape as that desired in the finished capsule, said tube having a cross-sectional area which is substantially less than the cross-sectional area of the finished capsule, forcing liquid filling material into said tube under sufficient pressure to cause that portion of said tube which is within said mold cavity to expand and fill said mold cavity, then simultaneously cutting off and sealing the expanded portion of said tube to form a capsule, and finally removing the finished capsule from the mold.
2. In capsule making apparatus of the class described, an orifice mechanism having a tube forming opening at one end thereof, means for forcing gelatine through said tube forming opening to form a tube, a hollow mold having an inlet opening and a mold cavity of substantially the same shape as that desired in the finished capsule, said inlet opening and said tube forming opening being aligned to permit the formed tube to be extruded into the mold, means for forcing liquid filling material through said tube during each capsule making operation, whereby the portion of the tube within said mold cavity is expanded to fill said mold cavity and shear means interposed between said mold and said orifice mechanism, said mold being spaced from said orifice mechanism a distance substantially equal to the thickness of said shear means.
3. In capsule making apparatus of the class described, an orifice mechanism having a tube forming opening at one end thereof, means for forcing gelatine through said tube forming opening to form a tube, a hollow mold having a mold cavity of substantially the same shape as that desired in the finished capsule, said mold cavity being normally completely closed except for an inlet opening which aligns with said tube forming opening whereby a portion of said tube is admitted into said mold cavity during each operation of said apparatus, shear means interposed between said orifice mechanism and said mold, said mold being spaced from the outlet of said orifice mechanism a distance substantially equal to the thickness of said shear means, means for injecting liquid filling material into said tube under substantial pressure during each capsule making operation whereby the portion of said tube within said mold cavity is expanded to fill that cavity, means for operating said shear means to cut off the expanded tube portion located within said mold cavity, and means for opening said mold to permit the removal of the capsule therefrom.
4. In capsule making apparatus of the class described, an orifice mechanism having a tube forming outlet opening at one end thereof, means for forcing gelatine through said tube forming opening to form a tube, a hollow mold having a mold cavity of considerably greater cross-sectional area than said tube forming opening, said mold cavity being normally completely closed except for an inlet opening which aligns with said

tube forming opening, whereby a portion of said tube is admitted into said mold cavity, shear means interposed between said orifice mechanism and said mold, said shear means, when open, providing an enclosed passageway between said tube forming opening and the inlet opening to said mold, means for injecting liquid filling material into said tube under substantial pressure during each capsule making operation whereby the portion of said tube within said mold cavity is expanded to fill said mold cavity, means for operating said shear means to cut off the expanded tube portion located within said mold cavity, and means for opening said mold to permit the removal of the capsule therefrom.

5. In capsule making apparatus of the class described, an orifice mechanism having a tube forming outlet opening at one end thereof, means for forcing gelatine through said tube forming opening to form a tube, a hollow mold having a mold cavity of substantially the same shape as that desired in the finished capsule, said mold cavity being normally completely closed except for an inlet opening which aligns with said tube forming opening whereby a portion of said tube is admitted into said mold cavity during each operation of said apparatus, means for forcing liquid filling material through said tube during each capsule making operation, whereby the portion of the tube within said mold cavity is expanded to fill said mold cavity and shear means interposed between said orifice mechanism and said mold, said mold being spaced from the outlet of said orifice mechanism a distance substantially equal to the thickness of said shear means, said shear means including guide means and opposed knife members movable from a normally separated position to an engaging position, and said guide and said knife means providing an enclosed passageway between said tube forming opening and the inlet opening to said mold when said knife members are in the separated position.

6. In capsule making apparatus of the class described, an orifice mechanism having a tube forming opening at one end thereof, means for forcing gelatine through said tube forming opening to form a tube, a hollow mold having a mold cavity of considerably greater cross-sectional area than said tube forming opening, said mold cavity being normally completely closed except for an inlet opening which aligns with said tube forming opening whereby a portion of said tube is admitted into said mold cavity, shear means, including spaced shear members and guide means for said members, interposed between said orifice mechanism and said mold, said mold being spaced from the outlet of said orifice mechanism a distance substantially equal to the thickness of said shear means, said shear members and said guide means when open providing an enclosed passageway between said tube forming opening and the inlet to said mold, means for injecting liquid filling material into said tube under substantial pressure during the capsule making operation whereby the portion of said tube within said mold cavity is expanded to fill said mold cavity, means for moving said shear members into engagement with each other following each tube expanding operation, said engaging shear members simultaneously cutting off and sealing the expanded tube portion located within said mold cavity, and means for opening said mold to permit the removal of the capsule therefrom.

7. In capsule making apparatus of the class described, an orifice mechanism having a tube

- forming opening at one end thereof, means for forcing gelatine through said tube forming opening to form a tube, a pair of oppositely arranged, pivotally supported mold members movable from a normal, engaged position to a separated position, said mold members being provided with cooperating, hollowed out portions which, when said mold members are in said engaged position, define a mold cavity which is completely closed except for an opening which aligns with said tube forming opening whereby a portion of said tube is admitted into said mold cavity during each capsule making operation, shear means interposed between said orifice mechanism and said mold, said shear means when open providing an enclosed passageway between said tube forming opening and the inlet opening to said mold, means for injecting liquid filling material into said tube under substantial pressure during each capsule making operation whereby the portion of said tube within said mold cavity is expanded to fill said mold cavity, means for operating said shear means to cut off and seal the expanded tube portion located within said mold cavity, and means for moving said mold members from said engaged position to said separated position following each operation of said shear means to effect the removal of the capsule from said mold cavity.
8. In capsule making apparatus of the class described, an orifice mechanism having a tube forming opening at one end thereof, means for forcing gelatine through said tube forming opening to form a tube, a hollow mold having an inlet opening and a mold cavity of substantially the same shape as that desired in the finished capsule, said inlet opening and said tube forming opening being aligned to permit the formed tube to be extruded into the mold, means for forcing liquid filling material through said tube during each capsule making operation, whereby the portion of the tube within said mold cavity is expanded to fill said mold cavity and shear means interposed between said mold and said orifice mechanism, said mold being spaced from said orifice mechanism a distance substantially equal to the thickness of said shear means, said shear means being movable from a normal, separated position to an engaged position to cut off said tube and to close said tube forming opening.
9. In capsule making apparatus of the class described, an orifice mechanism having a tube forming opening at one end thereof and a filling tube located centrally of said opening, means for forcing gelatine through said tube forming opening to form a tube, a hollow mold having an inlet opening and a mold cavity of substantially the same shape as that desired in the finished capsule, said inlet opening and said tube forming opening being aligned to permit the formed tube to be extruded into the mold means for forcing filling material through said filling tube to fill and expand said gelatine tube simultaneously with the formation thereof, shear means interposed between said mold and said orifice mechanism, said mold being spaced from the outlet of said orifice mechanism a distance substantially equal to the thickness of said shear means, said shear means including cooperating members movable across said outlet opening from a normal, separated position to an engaging position to sever said tube and to close said tube forming opening and said filling tube, and means actuatable during each operation of said apparatus to move said cooperating shear members from said separated position to said engaging position.
10. In capsule making apparatus of the class described, an orifice mechanism having a tube forming opening at one end thereof, means for forcing gelatine through said tube forming opening to form a tube, a hollow mold having a mold cavity of considerably greater cross-sectional area than said tube forming opening, said mold cavity being normally completely closed except for an inlet opening which aligns with said tube forming opening whereby a portion of said tube is admitted into said mold cavity, shear means which includes a pair of shear members movable from a normal, separated position to an engaging position interposed between said orifice mechanism and said mold, said shear means when open providing an enclosed passageway between said tube forming opening and the inlet opening of said mold, means for injecting liquid filling material into said tube under substantial pressure during each capsule making operation whereby the portion of said tube within said mold cavity is expanded to fill said mold cavity, means for moving said shear members from said separated to said engaging position following each tube expanding operation to cut off the expanded tube portion located within said mold cavity, means for opening said mold to permit the removal of the capsule therefrom, said shear members when in the engaged position serving to close and seal said tube forming opening.
11. In capsule making apparatus of the class described, an orifice mechanism having a tube forming opening at one end thereof, means for forcing gelatine through said tube forming opening to form a tube, a hollow mold having an inlet opening and a mold cavity of substantially the same shape as that desired in the finished capsule, said inlet opening and said tube forming opening being aligned to permit the formed tube to be extruded into the mold, means for forcing liquid filling material through said tube during each capsule making operation, whereby the portion of the tube within said mold cavity is expanded to fill said mold cavity, a plate member provided with at least one guide slot interposed between said orifice mechanism and said mold, said mold being spaced from said orifice mechanism a distance substantially equal to the thickness of said plate member, and shear means supported in said guide slot for movement from a normal, separated position to an engaging position.
